UNITED STATES PATENT OFFICE

2,115,483

ARRANGEMENT FOR CONTROLLING FIREARMS

Raymond Defives, Brussels, Belgium, assignor to
Servo-Frein Dewandre Société Anonyme, Liege,
Belgium

Application March 27, 1936, Serial No. 71,267
In France April 3, 1935

6 Claims. (Cl. 89—27)

My invention relates to control arrangements for fire arms and is concerned specially with a pneumatic device for the remote control of machine guns on aeroplanes, and in particular those 5 mounted on the wings of aeroplanes.

The invention consists in uniting into a compact device of reduced weight and bulkiness, fixed to the machine gun support, the various auxiliary compressed or depressed fluid motors intended to operate the controls for manoeuvring, for cocking, for firing and for locking the said 10 machine gun, which controls are not fixedly connected to the auxiliary motors, so as to permit a rapid removal and replacement of the gun on its 15 support.

Further, the invention provides the use, for the distribution of pneumatic fluid to the various auxiliary motors, of either electropneumatic valves, or of a distributing cock or push valves, 20 or again the combined use of such distributing systems in such a way as to obtain a rapid actuation of the machine gun controls, whatever be the distance between the gun and the operator's post.

25 In one embodiment of the pneumatic operating mechanism, the latter comprises a device for locking the machine gun, which is unlocked automatically by the cocking operation of the gun.

Various embodiments of the invention are 30 hereinafter described with reference to the accompanying drawings in which:

Figure 1 is an elevation partly in vertical section of an embodiment of the unit comprising auxiliary motors and operating on compressed air, as applied to a machine gun of known type, the various members being shown in their positions of rest;

Figure 2 is a section on the line 2—2 of Figure 1;

Figure 3 is a section on the line 3—3 of Figure 1;

Figure 4 is a plan of the arrangement shown in Figure 1;

Figure 5 is a diagrammatic view of a pneumatic fluid control system operable by electro-magnetic valves and designed to be used when the apparatus is operated by compressed air.

Figure 6 is a diagrammatic view of a pneumatic fluid control system operable by electro-magnetic valves and designed to be used when the apparatus is operated by suction.

Figure 7 is a diagrammatic view of an alternative pneumatic apparatus operated by compressed air, with the fluid distribution controlled

by electro-magnetic valves and by a distributing cock.

Figure 8 is a longitudinal section of an alternative pneumatic apparatus having a locking arrangement shown in the disengaged position. 5

Figure 9 is a fragmentary view, similar to Figure 8, showing the locking arrangement in the engaged position.

Figure 10 is a diagrammatic vertical section of 10 a pneumatic push valve.

In the drawings, 10 designates the frame which supports the operating motors of the arrangement, and which is fixed at 11 and 12 to the supporting bolts of the machine gun butt 13.

A cylinder 14, integral with the said frame, has a piston 15 with a hollow stem 16 slidable at 17 and having at its end remote from the piston an abutment 18 for operating the cocking handle 19 of the machine gun when the piston 15 is displaced by compressed air admitted through the 20 port 20 in the motor cylinder 14. A spring 21 for returning the piston to its position of rest is provided within the hollow stem 16 and is fixed at one end, at 22, to the bottom of the said stem and at the other end, at 23, at the inlet end of the 25 cylinder 14.

A port 24 is provided in the wall of the cylinder 14, to allow for the escape of the air compressed through movement of the piston 15.

A second motor cylinder 25, arranged alongside the cylinder 14 and also integral with the frame 10 is provided with a piston 26 movable against the spring 28 by compressed fluid admitted through the port 27 provided in the wall of the cylinder 25. The entrance to this cylinder is closed by a stopper 30 through whose centre a stem 31 integral with the piston 26 slides in an airtight manner, which stem is connected at 32 to a connecting rod 33, linked at 34 to a bell crank lever 35—36 pivoted on a pin 37 supported in a convenient way by a member 38 mounted on the butt 13 of the machine gun. 30

35 A plane abutment 39 at the end of the lever 36, operates the trigger 40 provided for firing the machine gun. 40

A third double acting motor cylinder 41 arranged on the frame 10 laterally of the cylinder 14 opposite the cylinder 25, is provided with a piston 42 which can be moved in both directions by pneumatic fluid admitted either through the port 43 or the port 44 in the cylinder 41. 45

50 A stem 45, integral with the piston 42, slides in an airtight manner through the end wall of the cylinder 41 and is linked at 46 to one end of a lever 47 pivoted at 48 to the frame 10. The other

end 49 of this lever is bent and ends in a fork whose arms 49a and 49b engage one of the lateral projections 50 of the safety lock 51 provided on the butt of the machine gun (Figure 4).

5 Operation of the motor cylinders when the fluid is compressed air is as follows: electro-magnetic valves 52, 53, 54 and 55 (Figure 5) of any known type for distributing pneumatic fluid, are connected on the one hand through the pipe 10 56 to a compressed air reservoir, and on the other hand to each of the motor cylinders.

The valve 52 is connected through the pipe 20a to the port 20 in the cylinder 14. The valve 53 is connected through the pipe 27a to the port 27 15 in the cylinder 25. The valves 54 and 55 are connected respectively to ports 43 and 44 in the cylinder 41 through pipes 43a and 44a.

The coil of each electro-magnetic valve is connected by a conducting wire 58 to one of the poles 20 of a storage battery 57. The other pole of the battery 57 is connected by a wire 59 to a switch board provided within the operator's reach at the operator's place.

The operating circuit of the valve 52 for cocking 25 the machine gun comprises a reversing switch button 60 having two operative positions, which is connected by wires 61 and 62 to a reversing switch 63, the latter being connected by the wire 64 to the coil of the valve 52.

30 The switch 63 is a reversing switch of any ratchet driven type, whose lever 65 is controlled automatically by the movements of the piston 15 when the latter reaches the end of its operating stroke and is returned to its initial position 35 by resilient means.

The valve 53 which controls the trigger for firing the gun is operated electrically by a push button 66 connected through a wire 67 to the coil of the valve 53.

40 The two positions of the safety lock 51 are controlled by the valves 54 and 55, the coils of which may be connected to the battery through the wires 68 and 69 respectively and the throw over switch 70 which normally breaks the electric circuit. The switch board may be arranged 45 in such a manner that the operator by actuating one of the switches, may control one or more of the machine guns at will.

50 The operation of the arrangement is as follows:—in an aeroplane with machine guns provided in the wings, when the pilot or gunner wishes to fire he will at first cock the machine gun or guns by manipulating the switch 60 which 55 operates the valve 52 and connects the cylinder 14 to the compressed air source. Under the action of the pneumatic fluid the piston 15 is moved towards the right (Figures 1 and 5) and through the stem 16, and the abutment 18 moves 60 the cocking handle 19, which by this movement cocks the machine gun. When the piston 15 reaches the end of its travel it actuates the lever 65 and operates automatically the reversing switch 63, which breaks the circuit of the coil 65 of the valve 52, and so cuts off the compressed air from the cylinder 14 and connects the latter to the atmosphere. The piston returns then, to its position of rest under the action of the spring 21.

70 The cocking handle 19 being freed from the abutment 18 may move during firing without being impeded by the said abutment 18.

If it is necessary to cock afresh, the gunner actuates the switch 60 and the same effects will 75 be produced again owing to the new position

taken by the reversing switch 63 as a result of the previous operation.

The machine gun being cocked, when the gunner pushes the firing button 66 the valve 53 will be actuated and the fluid admitted to the cylinder 5 25 will operate through the piston 26, the stem 31 and the connecting rod 33, so as to rock the bell crank lever 35 and 36, the end abutment 39 of which will depress the trigger 40. To cease fire it is only necessary to break the circuit by 10 releasing the button 66, so that the piston 26 and the members controlled by it, will return to their original position under the action of the spring 28.

If the gunner wishes to engage the safety lock 15 to prevent any accidental firing of the machine gun on landing, or to disengage the said bolt to allow the gun to be operated, he will actuate the throw over switch 70 for closing the circuit of the coil of either the valve 54 or the valve 55, 20 which operate the desired displacement of the piston 42 in the double acting cylinder 41, which, through the stem 45 of the pivoted lever 47 and the fork 49, will actuate the projection 50 on the lock 51.

The action of the machine gun is so to say instantaneous, since the electropneumatic valves may be situated near to the device they operate. The metal bottle or reservoir (not shown) for the compressed air may likewise be located near to the devices to be operated, thus reducing to a 30 minimum the length of piping.

Since air in the bottle is compressed to a pressure of 20 to 25 kilograms, there is a pressure reducing valve on it to allow the working pressure to be decreased to 5 kilograms per square centimetre. It is essential also, that the compressed air used should be dry so as to prevent condensation, as a result of expansion, which would induce at high altitudes, the formation of icicles in the pipes, and would so stop the operation of the gun.

The device such as designed to be operated by compressed air allows a compact apparatus to be realized, having a minimum of both bulkiness and weight.

Electro-magnetic control according to the invention may be devised according to an alternative form shown in Figure 6, such as to operate 50 by means of the suction existing in the intake pipe of the internal combustion engines, or by means of a vacuum created in the reservoir 71 by a vacuum pump operated in any convenient manner.

The mechanical arrangement is substantially the same as for compressed air. Since the motive force is obtained in this alternative construction by the difference in pressure, between the degree of vacuum and atmospheric pressure movement 60 of the motor pistons will be effected by suction.

However, apparatus operating by suction are more bulky than those operated by compressed air.

Indeed, the size of the various operating cylinders must be such that at high altitudes the vacuum will still be sufficient to actuate the various controls of the gun.

According to another system of controlling auxiliary pneumatic motors, the motors operating the cocking and locking devices of the gun are connected to the compressed air source through a distributing cock 72 (Figure 7), whilst the motor actuating the trigger for firing the gun is connected to a fluid source by means of a 75

distributing valve 53 controlled electrically from the push button 66.

The cock 72 may be a three-way distributor of any type, which, in accordance with the position of a control handle 73 connects the fluid pressure pipe 56 discharging into said cock at 74, to any one of the pipes 20a, 44a, or 43a, entering the cock respectively at 75, 76 and 77.

A horse-shoe shaped channel 78 provided in 10 the plug of the cock allows the ports 75, 76 and 77 to be connected to the atmosphere by way of the port 80. In the position shown in Figure 7, the fluid feed pipe 56 is connected to the pipe 44a of the motor 41.

15 After operating any of the motors the control handle 73 is returned to, and held by any convenient means in an intermediate position, such as to cut off normally the communication between the fluid source and the motors, and connect these latter to the atmosphere.

In order to prevent the motor pistons from striking harshly the bottom of their respective cylinders under the action of pneumatic fluid, particularly in the case of the motor controlling 25 the machine gun cocking handle, the invention provides means for damping such blows.

One of these means comprises a cut away portion 81 (Figure 7) on one side of the piston stem 16, which permits air within the cylinder 14, 30 which is forced out by the movement of the piston 15, to escape through the port 24, until the cylindrical part 82 of this stem enters the bearing 17 and closes the port 24, so preventing further escape of the compressed air, which thus 35 forms an air cushion.

In the alternative embodiment shown in Figure 8, the apparatus is provided with a device for locking a machine gun whatever be the type of the latter. The locking device consists of a 40 cylinder 83 integral with the frame 10 and arranged at the side of the cylinder 14. A piston 84 provided with a stem 85, having a restriction 86, is provided for movement in the cylinder 83 against a spring 87 under the influence of compressed fluid admitted to it through the port 88.

In a guide 89 provided transverse to the axial plane common to the cylinders 14 and 83 at the extreme right of this latter, as shown in Figure 8, there is slidably mounted against the action of a 50 spring 90, a bolt 91 with a head 92. In the middle of this bolt there is an opening 93, through which the stem 85 projects, and this middle part is narrow so as to be able to engage the restriction 86.

55 A ramp 94 is formed at the extreme right of the stem 16, so as to lift the bolt 91 by acting on its head 92, when the stem is moved.

The operation of the locking arrangement is as follows—When having ceased firing, the gunner 60 wishes to lock the machine gun, he operates the control for the admission of fluid to the port 88. The piston 84 is moved towards the right under the influence of compressed air and moves with it the stem 85, whose end comes into contact with 65 the cocking handle 19, thus preventing movement of this latter at one point in its travel, and so mechanically locking the automatic means of the machine gun and stopping its fire.

In the meantime, the movement of the stem 85 70 has brought its restriction 86 so as to register with the narrow part of the bolt, allowing the latter to move under the influence of the spring 90, so as to engage the edges of the opening 93 on the restriction 86, thus preventing the stem 85 from 75 returning to the left when fluid pressure is re-

moved from the piston 84. At this moment, the mechanism is in the position shown in Figure 9.

In order to unlock the gun and so allow fresh firing, it is only necessary to effect the cocking operation. During this latter operation, movement of the stem of the piston 16 coacts with the head 92 of the locking bolt, through the ramp 94, so as to lift the bolt 91. The bolt 91 is thus disengaged from the restriction 86, whilst the stem 85 and the piston 84 return to their initial position under the influence of the spring 87.

10 In some cases of direct distribution of pneumatic fluid it will be of advantage to replace the distributing cock shown in Figure 7, by push valves, each auxiliary pneumatic motor being 15 controlled by a separate valve.

Such a valve is shown in Figure 10 and consists of a valve casing 95, in which two valves 96 and 97 lined with elastic material, connected by a stem 98, may be moved against a spring 99 under 20 the influence of pressure on the push-button 100, so as to connect the fluid inlet port 101 by way of chamber 102, with the fluid exit port 103, this latter being normally in communication with the port 104, communicating with the atmosphere. 25

It should be understood that the valve which has just been described may equally well be used for the control of any device operated by compressed fluid.

Finally, it should be understood that the pneumatic machine gun control mechanism is arranged in such a way as to allow the rapid removal and replacement of a damaged gun. Indeed, in order to remove the gun, it is sufficient to disconnect the pivotal connection 34, which 30 consists of a spring pressed ball joint, provided in the trigger control rod, and then to remove the gun laterally, which effects a simultaneous disconnection of the gun but from the supporting bolts 11 and 12, and also of the safety lock 51 35 and the cocking handle 19, from their respective controlling members.

To put the machine gun in place the operations are reversed.

What I claim is:

1. In a pneumatic device for the remote control of machine guns mounted on a support, the combination of a gun including a cocking device, a trigger and locking mechanism, a first auxiliary motor having a pneumatic driving member, resilient means acting upon said member, an abutment on said member to coact with the cocking device, a second auxiliary motor having a pneumatic driving member, resilient means acting upon the latter member, means actuated by said second driving member to coact with the trigger, and a double acting auxiliary motor having a pneumatic driving member for coacting with the locking means, said double acting auxiliary motor actuated in one direction to engage the locking means and in the other direction to disengage said locking means, said auxiliary motors being mounted on a common support to form a single monoblock unit independent of the gun and fixed onto the gun support to allow rapid removal and replacement of the gun from and to its support, and means for distributing compressed fluid from a distance to said pneumatic motors.

2. In a device for the remote control of machine guns, according to claim 1, characterized by 70 the fact that the means for distributing compressed fluid to the pneumatic motors comprise a fluid distributor for each pneumatic motor, three chambers formed in said distributor, the first of said chambers being in communication 75

with the source of fluid, the second chamber being in communication with the pneumatic motors, and the third chamber being in communication with the atmosphere, a valve in said first chamber, a seat in said chamber for said valve, a spring acting upon said valve, an elastic lining on the head of said valve to be normally pressed upon said seat by the combined action of said spring and of the compressed fluid acting on the underside of said valve, a second valve provided in the third chamber, a seat for said second valve, an elastic lining on said second valve to be pressed against the seat for the said second valve when the latter is actuated to cut the communication between the atmosphere and the pneumatic motor, and means integral with said second valve for depressing the said first valve and establishing communication between the source of compressed fluid and the motor when the said second valve is actuated.

3. In a pneumatic device for the remote control of the actuating members of a machine gun, the combination of a breech block and cocking means, a cylinder associated with the gun, a piston operating in the cylinder, a piston rod extending from the piston, fluid pressure means for operating the piston in one direction, a spring for operating the piston in the opposite direction, the free end of the piston rod when the piston is operated by fluid pressure extending into the path of movement of the cocking means to limit the movement of the breech block when the gun is fired and to automatically lock the cocking device.

4. In a pneumatic device for the remote control of the actuating members of a machine gun, the combination of a breech block and cocking means, a cylinder associated with the gun, a piston operating in the cylinder, a piston rod extending from the piston, fluid pressure means for operating the piston in one direction, a spring for operating the piston in the opposite direction, the free end of the piston rod when the piston is operated by fluid pressure extending into the path of movement of the cocking means to limit the movement of the breech block when the gun is fired and to automatically lock the cocking device, means for automatically locking the piston and its rod in operative position, and fluid pressure means for unlocking the piston and its rod to permit the spring to return the parts to normal position.

5. In a pneumatic device for the remote control of the actuating members of a machine gun, the combination of a breech block and cocking means,

a cylinder associated with the gun, a piston operating in the cylinder, a piston rod extending from the piston and formed with an annular groove, fluid pressure means for operating the piston in one direction, a spring for operating the piston in the opposite direction, the free end of the piston rod when the piston is operated by fluid pressure extending into the path of movement of the cocking means to limit the movement of the breech block when the gun is fired, and to automatically lock the cocking device, a guide arranged at right angles to the piston rod, a bolt slidably mounted in the guide, a spring acting on the bolt to cause the latter to engage in the groove in the piston rod when the latter is operated by fluid pressure and reaches the limit of its operating position, fluid operated means for disengaging the bolt from the groove to unlock the cocking means, and means for distributing fluid to the cylinder and the bolt disengaging means.

6. In a pneumatic device for the remote control of the actuating members of a machine gun, the combination of a breech block and cocking means, a cylinder associated with the gun, a piston operating in the cylinder, a piston rod extending from the piston and formed with an annular groove, fluid pressure means for operating the piston in one direction, a spring for operating the piston in the opposite direction, the free end of the piston rod when the piston is operated by fluid pressure extending into the path of movement of the cocking means to limit the movement of the breech block when the gun is fired and to automatically lock the cocking device, a guide arranged at right angles to the piston rod, a bolt slidably mounted in the guide, said bolt having its free end bevelled, a spring acting on the bolt to cause the latter to engage in the groove in the piston rod when the latter is operated by fluid pressure and reaches the limit of its operating position, a second cylinder, a piston and rod operating in said second mentioned cylinder, a tappet on the free end of the second mentioned piston rod to cooperate with the breech block and cocking means upon operation of the second mentioned piston by fluid pressure, a spring for returning the second mentioned piston to normal position, the second mentioned piston rod having a cam shaped recess near its free end with which the bevelled end of the bolt cooperates to release the first mentioned piston rod and free the cocking means when the second mentioned piston is actuated by fluid pressure.
